UNITED STATES PATENT OFFICE

JOHN P. LYNN, OF CHICAGO, ILLINOIS, ASSIGNOR TO DUR-O-LITE PENCIL CO., OF CHICAGO, ILLINOIS, A CORPORATION OF ILLINOIS

CLIP

Application filed July 20, 1929. Serial No. 379,659.

This invention relates to clips for pencils, hereinafter described. The edges of said extensions or lugs 15 may be perpendicular to the plate portion 11 as shown in Fig. 5 or they may be oblique thereto as shown in Fig. 7. The ends of extensions or lugs 15 are 55 preferably rounded to facilitate mounting upon the pencil, pen or the like.

Other objects, advantages and capabilities 10 will later more fully appear.

My invention further resides in the combination, construction and arrangements of parts illustrated in the accompanying drawings, and while I have shown herein a preferred embodiment I wish the same to be understood as illustrative only and not limiting the scope of my invention.

In the drawings,

Figure 1 is a longitudinal view of the upper end of a pencil, partly in section, with the improved clip mounted thereon,

Fig. 2 is a section on the line 2—2 of Fig. 1,

Fig. 3 is a section on the line 3—3 of Fig. 1,

Fig. 4 is a sectional detail on the line 4—4 25 of Fig. 1,

Fig. 5 is a sectional view of an intermediate part of the pencil on the line 5—5 of Fig. 2 showing the clip in juxtaposition thereto,

Fig. 6 is a perspective view of the clip, and

Fig. 7 is a sectional detail of a pencil showing a somewhat modified clip mounted thereon.

Referring to the drawings the clip comprises a springy portion 10 which is curved inwardly at one end and gives into a plate portion 11 which is intended to be applied to the surface of the pencil. At its other end the springy portion 10 carries a smooth curved member, for example a sphere 12, which is adapted to engage the fabric forming the outer wall of the pocket and permit same to pass readily and safely between the springy portion 10 of the clip and the pencil body 13.

The longitudinal edges of the plate portion 11 are turned inwardly 90° to form two flanges 14, said flanges having integral therewith extensions or lugs 15 which are intended 50 to extend into the wall of the pen or pencil as

The pencil body 13 is suitably prepared for the reception of the clip. The outer surface of said body is provided with two longitudinal grooves or depressions 16 which are intended to receive the flanges 14. Inwardly of said flanges extend slots 17 adapted to receive the extensions or lugs 15. The slots 17 preferably extend through the wall of the 65 body 13 of the pencil or the like into a lead magazine 18 or other chamber therein.

The slots 17 are somewhat smaller than the lugs 15 so that the latter have a tight drive fit therein. The grooves 16 are also preferably somewhat smaller than the flanges 14 to assist in retaining the clip in mounted position and also to cause the outer sides of the grooves to make close contact with flanges 14 at the visible lines of contact therebetween. 75 The difference in size between the slots 17 and the grooves 16 and the parts of the clip received therein depends upon the elasticity of the material from which the body is made.

In all cases it is such that when said parts 80 are driven into position they are held by a substantial frictional force and the material of the body 13 adjacent thereto, particularly the material adjacent the edges of the lugs 15, is under substantial compression so that 85 movement of said parts is strongly opposed.

The relation of the portion 10 of the clip to the plate portion 11 thereof is preferably such that when the latter is pressed into seating relation upon the pencil body, the springy portion 10 is bent outwardly and the ball 12 pressed against the surface of the pencil body. 90

It will be readily understood that when the clip is pressed into mounted position the friction between the edges of the slots 17 and the lugs 15 strongly opposes any force tending to raise the plate 11 directly from the pencil body. However, the principal forces experienced by said plate in normal use of the pencil or the like are of a rotary nature and 100

are exerted thereon by the curved end of the springy portion 10 of the clip. Movement due to such forces is opposed by said friction and also by a jamming effect produced between the lugs 15 and slots 17. Such jamming effect is accentuated by the state of compression of the body material adjacent said lugs owing to the tight drive fit therebetween. When the slots 17 extend inwardly and downwardly as shown in Fig. 7 the obliquity of the sides of the slots nearest the free end of the clip receives and directly opposes the thrust due to any tendency of the plate 11 to rotate.

15 When the clip is pressed into position the ends of the lugs 15 preferably extend into the chamber 18. The projecting extremities of said lugs are preferably sheared off by an operation which leaves the burrs facing each other as shown at 19 in Fig. 2. Such burrs enter into the material of the pencil body and aid in holding the clip in position. It is obvious that similar burrs, or deformation or the like can be produced otherwise during 20 or subsequent to the driving of the clip into position.

The grooves 16 and slots 17 may be formed or produced in any suitable way. Thus, they may be formed during the moulding of the 30 pencil body. In the case of certain relatively plastic materials they may be subsequent to moulding by a male die co-operating with a female die on a mandrel or they may be cut out mechanically by suitable means.

35 I claim:

1. In combination, a body and a pocket clip, said clip having projecting lugs and said body having openings into which said lugs enter with a tight drive fit.

40 2. In combination, a body and a pocket clip, said clip being provided with a plate portion having lugs extending transversely therefrom and said body being provided with openings in which said lugs are received with a tight drive fit.

45 3. In combination, a body and a pocket clip, said clip being provided with a plate portion having inwardly turned edges and lugs extending inwardly from said edges and 50 said body having grooves adapted to receive said edges and openings extending inwardly from said grooves in which said lugs are received with a tight drive fit.

55 4. In combination, a body and a pocket clip, said clip being provided with a plate portion having inwardly turned edges and lugs extending inwardly from said edges and 60 said body having grooves adapted to receive said edges with a tight drive fit and openings extending inwardly from said grooves in which said lugs are received with a tight drive fit.

65 5. In combination, a body and a pocket clip, said clip comprising a springy member having a free end and projecting lugs at the

other end and said body having openings into which said lugs enter with a tight drive fit in such a manner that the free end presses against the body when the clip is in mounted position.

70 6. In combination, a body and a pocket clip, said clip comprising a springy member having a free end and a plate at the other end, 75 said plate having lugs extending transversely therefrom and said body being provided with openings in which said lugs enter with a tight drive fit in such a manner that the free end presses against the body when the clip is in mounted position.

75 7. In combination, a body and a pocket clip, said clip comprising a springy member and laterally extending lugs of substantial width and integral with the springy member, said body being provided with openings in which said lugs are entered in such a manner that outward bending of the springy member causes said lugs to jam within said openings.

80 8. In combination, a body and a pocket clip, said clip comprising a springy member and plate portion carrying transverse lugs which are received tightly within openings in said body in such a manner that outward bending of the springy member causes said lugs to jam within said openings.

85 9. In combination, a body and a pocket clip, said clip comprising a springy member and plate portion carrying inturned flanges and transverse lugs, said flanges being received tightly in grooves in the body and said lugs entering tightly openings in said body in such a manner that outward bending of 90 said springy member causes said lugs to jam within said openings.

100 10. In combination, a body and a pocket clip, said clip having projecting lugs and said body portion having openings through the wall thereof, said lugs entering with a tight drive fit into said openings and being burred on the inner side of said wall.

105 11. In combination, a body and a pocket clip, said clip being provided with a plate portion having lugs extending transversely therefrom and said body being provided with 110 openings through the body wall in which said lugs are received with a tight drive fit, the ends of said lugs being burred on the inner side of said wall.

115 12. In combination, a body and a pocket clip, said clip being provided with a plate portion having inwardly turned edges and lugs extending inwardly from said edges and 120 said body having grooves adapted to receive said edges and openings extending inwardly through the wall of said body in which said lugs are received with a tight drive fit, the ends of said lugs being burred on the inner side of said wall.

125 13. In combination, a body and a pocket clip, said clip having oblique projecting lugs

and said body having oblique openings into which said lugs enter with a tight drive fit.

14. In combination, a body and a pocket clip, said clip being provided with a plate portion having obliquely projecting lugs extending therefrom and said body being provided with oblique openings in which said lugs are received with a tight drive fit.

15. In combination, a body and a pocket clip, said clip being provided with a plate portion having inwardly turned edges and lugs extending obliquely inwardly from said edges and said body having grooves adapted to receive said edges and oblique openings extending inwardly from said groove in which said lugs are received with a tight drive fit.

16. In combination, a body and a pocket clip, said clip having integral projecting lugs of substantial width inserted in openings in said body in such a manner that outward force applied to the clip causes said lugs to jam in said openings.

17. In combination, a body and a pocket clip, said clip having integral projecting lugs and said body portion having openings through the wall thereof, said lugs entering into said openings and being burred on the inner side of said wall.

18. In combination, a body and a pocket clip, the clip having an inwardly turned edge carrying projecting lugs and the body being provided with openings to receive the lugs.

19. In combination, a body and a pocket clip, the clip having an inwardly turned integral lug, and the body having an opening adapted to receive the lug with a drive fit.

20. In combination, a body and a pocket clip, the clip having an inwardly turned edge carrying projecting lugs and the body being provided with a groove adapted to receive the edge, and with openings extending from the groove adapted to receive the lugs with a drive fit.

In testimony whereof, I have hereunto set my hand this 11th day of July, 1929.

JOHN P. LYNN.
